UNITED STATES PATENT OFFICE.

WILLIAM A. LOTZ, OF NEWARK, NEW JERSEY, ASSIGNOR TO THE R. NEUMANN HARD-WARE CO., A CORPORATION OF NEW JERSEY.

BAG-FRAME FASTENER.

1,187,751.

Specification of Letters Patent. Patented June 20, 1916.

Application filed March 31, 1916. Serial No. 87,987.

To all whom it may concern:

Be it known that I, WILLIAM A. LOTZ, a citizen of the United States, residing at Newark, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in that class of fastening or locking devices, such as are usually employed with the hinged sections of bag-frames, and the like; and, the invention has 20 reference, more particularly, to a novel bag-frame fastener which is very simple in its construction and in its operation, and which comprises in connection with a shell or casing adapted to be secured upon one of the 25 frame-sections, a slide and its catch-engaging post or finger, a push-device or button for releasing a retaining spring from its holding engagement with said slide, and means for bringing the said slide after its 30 release again into its holding engagement with said retaining spring.

The present invention has for its principal objects to provide a bag-frame fastener of the general character just stated; and, furthermore, to provide a fastening device for bag-frames, and the like, which has a neat appearance, and in which there are but few internal parts, such parts being arranged so as to render the operations of 40 said fastening device easy and effective, and at the same time obviating the liability or chance of any disarrangement of the various parts.

Other objects of the present invention not 45 at this time more particularly enumerated will be clearly understood from the following detailed description of the present invention.

With the various objects of the present 50 invention in view, the said invention consists, primarily, in the novel bag-frame fastener hereinafter set forth; and, the invention consists, furthermore, in the novel arrangements and combinations of the several 55 devices and parts, as well as in the details

of the construction of the said parts, all of which will be more fully described in the following specification, and then finally embodied in the clauses of the claim which are appended to and which form an essential 60 part of the said specification.

The invention is clearly illustrated in the accompanying drawings, in which:—

Figure 1 is a plan or top view of a bag-frame fastener representing one embodiment 65 of the principles of the present invention, said view illustrating the fastener in its mounted position of one of the usual bag-frame sections and in its locked engagement with the other frame-section; and Fig. 2 is 70 a front or face view of the said bag-frame fastener, and a longitudinal vertical sectional representation of the frame-section upon which the fastener is mounted, as well as a transverse sectional representation of 75 a catch with which the other frame-section is provided and with which catch a locking bolt or post of the said fastener is shown in its locked or holding engagement. Fig. 3 is a bottom view of the said bag-frame fastener; Fig. 4 is a horizontal sectional representation, said section being taken directly beneath the top plate of the shell or casing of the fastener; Fig. 5 is a longitudinal vertical section of the fastener, said section being represented as taken on line 5—5 in Fig. 80 85 1, looking in the direction of the arrow x; Fig. 6 is a similar sectional representation of the same parts shown in said Fig. 5, but illustrating the slide-retaining spring in its 90 depressed position for releasing the slide, and the locking or holding bolt or post from its retained engagement with the hasp or catch of the one frame-section; and Fig. 6^a is a central longitudinal vertical section of 95 the bag-frame fastener, said Figs. 3, 4, 5, 6 and 6^a being made on an enlarged scale. Fig. 7 is a front or face view of a modified form of bag-frame fastener, but still embodying the principal features of the present 100 105 invention and a longitudinal vertical sectional representation of the one frame-section upon which the fastener is mounted, as well as a transverse sectional representation of the hasp or catch with which the other frame-section is provided and with which hasp or catch the locking bolt or post of the said bag-frame fastener is shown in its locked or holding engagement. Fig. 8 is a bottom view of the said bag-frame fastener;

110

Fig. 9 is a horizontal sectional representation of the same, said section being taken directly beneath the top-plate of the shell or casing of the fastener; Fig. 10 is a longitudinal vertical section of the said fastener, similar to the section represented in said Fig. 5 above-mentioned; and Fig. 11 is a central longitudinal vertical section of the said bag-frame fastener, said Figs. 8, 9, 10 and 11 being all made on an enlarged scale.

Similar characters of reference are employed in all of the said above described views, to indicate corresponding parts.

Referring now to the several figures, the reference-characters 1 and 2 indicate fragmentary parts of the two usual hinged members of a bag-frame, adapted to be closed so that the frame-section 2 will lie within the frame-section 1. At the proper point, the said frame section 2 is provided with the usual inwardly extending hasp or locking member 3.

Referring now more particularly to Figs. 1 to 6 inclusive, the reference-character 4 indicates a main chambered shell or casing, comprising longitudinally extending sides 5, ends 6 and 7, and a top 8. Extending from the lower marginal edges of the said ends 6 and 7 are suitably formed fastening lugs, as 9, which are inserted in the lug-receiving holes or slots 10 correspondingly disposed in the frame-section 1, and are suitably bent against the inner face of the said frame-section for permanently securing the said shell or casing 4 in its position upon the upper face of said frame-section. The end 6 of the said shell or casing is made with a finger or push-piece receiving opening, as 11, and in the top 8 is a suitable push-button receiving hole 12.

The reference-character 13 indicates a suitably formed cup-shaped element which may be employed, if desired, being suitably secured upon the outer face of said top 8, by means of fastening lugs 14, or other suitable fastening means, and surrounding the said opening 12, in a manner substantially as indicated in Fig. 6^a of the drawings.

Suitably secured to the inner face of the end 7 of the said shell or casing 4, by means of a rivet, as 15, or any other suitable fastening means, is the attaching end-portion 17 of a longitudinally extending leaf-spring 16, the said spring being arranged in alignment beneath the push-button receiving hole 12 in the top 8 of the shell or casing, and being provided upon its free end-portion with an upwardly projecting slide-retaining or holding teat or projection, as 18, formed with an inclined or chamfered surface-portion 19. Suitably disposed within the said hole 12 is a push-button, as 20, the lower portion of said button projecting into the chambered part of the shell or casing 4, and resting directly upon the upper surface

of said leaf-spring 16, as shown, and for the purpose of the depressing the said free end-portion of the said spring, as will be clearly evident from an inspection of the several figures of the drawings. To prevent displacement of the said push-button, its lower end-portion is made with a retaining flange 21 somewhat larger in cross-area than that of the hole 12, as shown. Other means may, however, be employed to prevent the outward displacement of the said push-button 20, as will be evident.

Movably disposed within the chambered part of the said shell or casing 4, and capable of a sliding movement, back and forth, between the longitudinally extending sides 5, is a retaining slide comprising a main body or plate 22, a pair of longitudinally extending marginal guide-members, as 23, projecting upwardly and at right angles from the said body or plate, and a pair of longitudinally extending fingers 24. Mounted upon said fingers 24 are the one end-portions of coiled springs 25, the other end-portions of said springs bearing upon the end-portion 17 of the spring 16, substantially as shown. Upon its opposite end-portion, the said main body or plate 22 is provided with a finger or push-piece, as 26, which extends into and through the previously mentioned receiving opening 11 in the end 6 of the main shell or casing 4. At the proper location, one of the said guide-members 23 of the slide is provided with a marginal retaining lug or finger, as 27, which extends laterally or crosswise, with relation to the main shell or casing 4, above the upper surface of the leaf-spring 16, and under normal initial conditions is in retained or held engagement with the teat or projection 18 of the leaf-spring, as indicated in Figs. 4 and 5 of the drawings. Suitably connected with and extending in a downward direction from the lower face of the said main plate or body 22 of the slide is the usual locking post or hasp-engaging finger 28 of the bag-frame fastener, said post or finger extending into and through and being slidably disposed in a longitudinally disposed slot 30 of the closing or bottom-plate 29 with which the shell or casing 4 may be provided, and a corresponding opening 30' in the frame-section 1, clearly evident from an inspection more particularly of Fig. 6^a of the drawings.

In Figs. 1 to 5 inclusive, I have shown the several elements of the bag-frame fastener in their locked or retained engagement, when the post or finger 28 is in its locked or holding engagement with the hasp of the frame-section 2, to retain the two frame-sections 1 and 2 in their closed relation.

The operation of the device will be clearly understood from an inspection of Figs. 4, 5

and 6 of the drawings. When the push-button 20 is depressed, the leaf-spring 16 is caused to assume the lowered position shown in Fig. 6 of the drawings, thus withdrawing the stud or projection 18 from its holding engagement with the lateral extending retaining lug or finger 27 of the slide. Immediately, the compressed coiled springs 25 will cause the slide to move in the direction of the arrow *y*, in Fig. 5, so as to bring the said lug or finger 27 upon the opposite side of the stud or projection 18, with the push-piece 26 of the slide projecting much farther from the opening 11 in the end 6 of the main shell or casing of the fastener. When the said lug or finger 27 has passed beyond the said stud or projection 18, it will be evident that the locking post or hasp-engaging finger 28 will also have moved from its retained engagement with the hasp 3 of the frame-section 2, so that the two frame-sections 1 and 2 can be brought into their opened relation. At the same time, the leaf-spring 16 has also returned to its normal initial position. To bring the various devices and parts again into their locked relation, the two-frame sections 1 and 2 are first closed, so as to bring the hasp 3 into its alined relation, or into the path of movement of the post or hasp-engaging finger 28. The push-piece 26 is now forced in an inward direction, so as to move the slide in the reverse direction from that indicated by the arrow *y*, the lug or finger 27 riding upon the inclined surface 19 of the stud or projection 18, and over the latter, thus depressing the leaf-spring sufficiently, until the said lug or finger 27 has passed said stud or projection 18, with the parts again in their locked or retained relation, as will be clearly evident and as indicated in Figs. 4 and 5 of the drawings.

Referring now to the modification of bag-frame fastener illustrated in Figs. 7 to 11 inclusive, the main box, shell or casing comprises a top 31, formed with an opening 32, longitudinally extending sides 33, and the ends 34, the opening in one of the ends, as in the construction herein-before described, being dispensed with in the present construction. The ends 34 are provided with the usual fastening lugs or tongues, as 35, which are inserted through the usual openings in the frame-section 1 and are clamped upon the inner face of the said frame-section in the usual manner. Attached to the inner face of one of the said ends 34, by means of a rivet 36, or otherwise, is the attaching end-portion 38 of a longitudinally extending leaf-spring 37, the said spring being arranged in alinement beneath the said opening 32, and being provided upon its free end-portion with an upwardly projecting slide-retaining or holding stud or projection 39, formed with an inclined or chamfered

surface-portion 40. Rotatably mounted upon the upper surface of the said main box, shell or casing is a manipulating element or finger-piece, as 41, provided upon its lower part with a reduced neck-portion 42 which extends into the said opening 32 and projects beneath the lower surface of the said top, substantially as illustrated in Figs. 10 and 11 of the drawings. The said manipulating element or finger-piece 41 is formed with a cup portion, as 43, in which is loosely disposed a push-button 44 provided upon its lower portion with an annular flange, as 45, resting directly upon the upper surface of the said leaf-spring 37, as shown in said Fig. 80. Suitably mounted and secured upon the said neck-portion 42 of the manipulating element or finger-piece 41 is a disk-shaped element, as 46, having an arc-shaped portion provided with teeth 47, and having a pair of angular portions, as 48 and 49, the purposes of which will be presently described. Movable disposed within the said box, shell or casing, and capable of a sliding movement, back and forth, between the longitudinally extending sides 33, is a retaining slide comprising a main body or plate 50, and a pair of upwardly projecting and longitudinally extending marginal guide-members, as 51 and 52, the member 51 being made with ratchet-like teeth 53, or the like, adapted to mesh with the herein-before-mentioned teeth 47 of the disk-shaped element 46. The other member 52 of the said slide is provided with a marginal retaining lug or finger, as 54, which extends laterally or crosswise, with relation to the main shell or casing, and under normal initial conditions is in retained or held engagement with the stud or projection 39 of the leaf-spring 37, as indicated in Figs. 9 and 10 of the drawings. At its one end, the said main body or plate 50 has a longitudinally extending finger, as 55, upon which is mounted the one end-portion of a coiled spring 56, the other end-portion of said spring bearing upon the end-portion 38 of the leaf-spring 37. Suitably connected with and extending downwardly from the lower face of the said main body or plate 50 is a locking post or hasp-engaging finger 57 which extends into and through, and is slidably disposed in a longitudinal slot or opening, as 59 of a closing or bottom-plate 58 with which the shell or casing of the bag-frame fastener may be provided, and the corresponding opening 30' in the frame section 1. In said Figs. 7 to 11 inclusive, the several elements of the bag-frame fastener are shown in their locked or retained engagement, when the said post or finger 57 is in its locked or holding engagement with the hasp 3 of the frame-section 2, to retain the two frame-sections 1 and 2 in their closed relation.

The operation of this modified bag-frame fastener is as follows:—When the push-button 44 is depressed, the leaf-spring 37 is forced in a downward direction, sufficiently to withdraw the stud or projection 39 from its holding engagement with the laterally extending retaining lug or finger 54 of the slide. Immediately, the compressed coiled spring 56 will cause the slide to move in the direction of the arrow z , in Fig. 10, so as to bring the said lug or finger 54 upon the opposite side of the retaining stud or projection 39. When the said lug or finger 54 has thus passed beyond the said stud or projection 39, it will be evident that the locking post, or hasp-engaging finger 57 will also have moved from its retained engagement with the hasp 3 of the frame-section 2, so that the two frame-sections 1 and 2 can be brought into their opened relation. At the same time, the leaf-spring 37 has also returned to its normal initial position. During the movement of the slide in the direction of the arrow z , the teeth 53 of the slide has rotated the toothed disk-shaped element 46 in the direction of the arrow u , until the corner-portion 48 is brought into contact with the marginal guide-member 51, which as will be evident limits and controls the movement of the slide in the direction of the arrow z . To bring the various devices and parts again into their locked relation, the two frame-sections 1 and 2 are first closed, so as to move the hasp 3 into the path of the post or hasp-engaging finger 57. The manipulating element or finger piece 41 is now manually turned in the direction of the arrow v , see Fig. 9, until the cover-portion 49 of the element 46 is brought into contact with the guide-member 52, this movement of the said element 46 causing the slide to move in the reverse direction from that indicated by the arrow z , and causing the lug or finger 54 to ride upon the inclined surface 40 of the stud or projection 39, and over the latter, thus depressing the leaf-spring 37 sufficiently, until the said lug or finger 54 has passed said stud or projection 39, with the parts again in their locked or retained relation, as will be clearly evident.

Of course, I am fully aware, that changes may be made in the general arrangements and combinations of the several devices and parts, as well as in the details of the construction of the said parts, without departing from the scope of the present invention as set forth in the foregoing specification, and as defined in the clauses of the claim which are appended to the said specification. Hence, I do not limit my present invention to the exact arrangements and combinations of the devices and parts as described in the said specification, nor do I confine myself to the exact details of the construction of the

said parts, as illustrated in the accompanying drawings. 65

I claim:—

1. A bag-frame fastener comprising a casing provided in its top with an opening, a lock-post-carrying slide within said casing, a leaf-spring within said casing, said spring having a portion movably disposed between the inner surface of said top and the upper surface of said slide, a push-piece within the opening in said top for depressing said spring, and a retaining means connected with said spring normally in holding engagement with said slide. 70

2. A bag-frame fastener comprising a casing provided in its top with an opening, a lock-post-carrying slide within said casing, said slide being provided with marginal guide-members, a retaining lug extending from one of said guide-members, a leaf-spring within said casing, a push-piece within the opening in said top for depressing said leaf-spring, and a retaining stud connected with said spring normally in holding engagement with said retaining lug of the slide. 80

3. A bag-frame fastener comprising a casing consisting of a top provided with an opening, longitudinal side-walls, and end walls, one of said end-walls being also provided with an opening, a lock-post-carrying slide within said casing, a push-piece connected with and extending longitudinally from one end of the said slide into and through the opening in the one end-wall of said casing, a leaf-spring within said casing, said spring having a portion movably disposed between the inner surface of said top and the upper surface of said slide, a push-piece within the opening in said top for depressing said spring, and a retaining means connected with said leaf-spring normally in holding engagement with said slide. 90

4. A bag-frame fastener comprising a casing consisting of a top provided with an opening, longitudinal side-walls, and end walls, one of said end-walls being also provided with an opening, a lock-post-carrying slide within said casing, a push-piece connected with and extending longitudinally from one end of the said slide into and through the opening in the one end-wall of said casing, said slide being provided with marginal guide-members, a retaining lug extending from one of said guide-members, a leaf-spring within said casing, a push-piece within the opening in said top for depressing said leaf-spring, and a retaining stud connected with said spring normally in holding engagement with said retaining lug of the slide. 110

5. A bag-frame fastener comprising a casing, consisting of a top provided with an

- opening, longitudinal side-walls, and end walls, one of said end-walls being also provided with an opening, a lock-post-carrying slide within said casing, a push-piece connected with and extending longitudinally from one end of the said slide into and through the opening in the one end-wall of said casing, spring-receiving fingers connected with and extending longitudinally from the other end of said slide, coiled springs mounted upon said fingers, said slide being provided with marginal guide-members, a retaining lug extending from one of said guide-members, a leaf-spring within said casing, a push-piece within the opening in said top for depressing said leaf-spring, and a retaining stud connected with said spring normally in holding engagement with said retaining lug of the slide. 25
